UNITED STATES PATENT OFFICE.

THOMAS MENZIES, OF PRATT, MANITOBA, CANADA.

ADDRESSING AND WRAPPING MACHINE.

Application filed December 20, 1924. Serial No. 757,206.

The invention relates to improvements in addressing and wrapping machines and an object of the invention is to provide a machine which will wrap and address periodicals such as magazines and newspapers, the periodicals being fed into the machine and ejected therefrom with an addressed wrapper there-around.

A further object is to construct the machine so that a roll of wrapping paper can be used, the paper being fed into the machine from the roll, cut into the wrappers by the machine, the individual wrappers being addressed and gummed and subsequently wrapped around and stuck on the periodicals fed into the machine.

A further object is to provide convenient means for supporting a stack of addressing slugs and for separately inking the slugs and bringing them to a position such that they will print addresses on the wrapping paper as it is passed through the machine, the slugs being fed so that they successively address the wrapping paper at spaced intervals whereby each wrapper bears a distinct and desired address.

A further object of the invention is to provide means for collecting the slugs in the stack after the same have made the addressing impression.

A further object of the invention is to provide as part of the machine, a device into which the periodicals are successively fed and which rolls the periodicals and also applies the gummed and printed wrapper around the rolled periodical and further to provide means for successively gripping and withdrawing the wrapped and addressed periodicals.

A further object is to construct the machine so that it is entirely automatic in operation with the exception that the periodicals to be wrapped and addressed are successively fed into the same.

With the above and other minor objects in view which will become more apparent as the description proceeds, the invention consists essentially in the arrangement and construction of parts hereinafter more particularly described, reference being had to the accompanying drawings in which:

Fig. 1 is a front view of the machine.

Fig. 2 is a plan view thereof.

Fig. 3 is a rear view of the machine.

Fig. 4 is an end view.

Fig. 5 is a vertical sectional view longi-

tudinally and centrally through the machine.

Fig. 6 is a vertical sectional view at 6-6' Figure 2 and looking in the direction of the applied arrow.

Fig. 7 is a vertical sectional view at 7-7' Figure 2 and looking in the direction of the applied arrow.

Fig. 8 is a horizontal sectional view at 8-8' Figure 3 and looking in the direction of the applied arrow.

Fig. 9 is an enlarged detailed sectional view at 9-9' Figure 5.

Fig. 10 is a perspective view of the slug feeding roller.

Fig. 11 is a perspective view of the guide rods for the slugs and other parts associated therewith.

Fig. 12 is a perspective view of one of the slugs and showing the addressing plate associated therewith.

Fig. 13 is an enlarged detailed vertical sectional view showing the position of the periodical when it is finally wrapped.

In the drawings like characters of reference indicate corresponding parts in the several figures.

The machine hereinafter described, is designed to provide a wrapper for periodicals such as magazines and newspapers, address the wrapper, apply and seal the addressed wrapper around the periodical and then eject the wrapped and addressed periodical from the machine, and the arrangement is such that the machine will work continuously to address and wrap any desired quantity of periodicals that are fed into the machine.

The base 1 of the machine is substantially rectangular and it is provided at the sides with upstanding side brackets 2 and 3 which are provided with suitably disposed bearings for cross shafts later described.

At the front end of the machine, the brackets carry an elevated cross shaft 4 which is mounted so that it can be withdrawn, and centrally on the shaft a roll of wrapping paper 5 is mounted, this being utilized to provide wrappers for the periodicals.

The end of the wrapping paper is passed downwardly between a pair of rollers 6 and 7, the roller 6 being carried by a cross shaft 8 mounted in suitable bearings 9 carried by the brackets, and the roller 7 being carried by a shaft 10 mounted in suitable bearings 11 carried by the base 1. After leaving the rollers 6 and 7, the paper passes between a further pair of rollers 12 and 13 mounted on

cross shafts 14 and 15 suitably carried in bearings 16 and 17 provided on the brackets and base 1.

The forward ends of the shafts 8 and 10 are fitted with intermeshing, similar gear wheels 18 and 18' and the forward ends of the shafts 14 and 15 are provided also with intermeshing gear wheels 19 and 19', and a driving pinion 20 meshes with the gear wheels 18' and 19', this pinion being suitably carried by the base 1.

At the front end of the machine I locate a pair of opposing standards 21 and 22 which support rotatably a cross shaft 23' on which I mount a slug feeding roller 23, the roller being provided with a peripheral groove or channel 24 enclosed between side flanges 24' formed on the roller. This roller is positioned centrally in advance of the roller 6 and is rotated at the same speed as the roller 6 by a gear wheel 23* secured to the shaft 23' and meshing with the gear 18. The standards carry a vertically disposed, guide, plate 25 and the upper end of the guide plate is fitted 25 with an opposing pair of arms 26 and 27 which terminate in inturned wings 26' and 27', the wings supporting the upper ends of a pair of suitably spaced guide rods 28 and 29. The lower ends of these guide rods terminate 30 above a horizontally disposed foot piece 30 formed at the lower end of the plate 25 and the rods are held in place by side wings 31 and 32 extending inwardly from a bracket 33 secured permanently to the plate 25. The foot 35 piece 30 enters the channel 24 and just clears the face of the roller 23. The foot piece, however, is slightly narrower than the width of the channel (see Figure 4).

The guide rods are adapted to slidably support a stack of similar slugs 34, the slugs being provided with vertically disposed spaced openings 35 and 35' slidably receiving the rods. The ends of the slugs are also vertically slotted as indicated at 36 and 36', these 45 slots communicating with the openings 35 and 35' and being adapted to receive the wings 26' and 27', and 31 and 32.

The upper and lower faces of the slugs are curved concentric to the roller 23. The slugs 50 are provided on their under faces with end legs 37 and 37' which ride the face of the roller 23 as each slug slides down into place against the face of the roller, and here it will be noted that the foot piece 30 supports the 55 lowermost slug, such foot piece entering between the legs and holding up the stack of slugs, whilst permitting of the lowermost slug to be removed and placed in the channel of the roller 23. The slugs are of such a size that 60 they fit within the channel of the roller between the flanges 24' and the face of each slug is provided with a dove tailed slot 38 which receives an addressing plate 39, this plate being frictionally held in place within 65 the dove tailed slot and having the letters or

other addressing characters thereon protruding and adapted in the rotation of the roller 23 to contact with the exposed face of the wrapping paper feeding in front of the roller 6.

The flanges of the roller 23 carry a pair of opposing pivoted gripping fingers 40 and 40' located on the inner sides of the flanges 24' and fitted with hooked ends 41 which pass slidably through the flanges and limit the 70 inward travel of the said pivoted fingers. Coiled springs 42 are interposed between the fingers and the flanges and normally hold the fingers in, with the result that as the said roller is rotating, the fingers will be swept 75 against the ends of the lowermost slug and will be pressed by the springs firmly into contact therewith.

Adjoining the fingers, the slug feeding roller is provided with opposing catches, 43' 85 and 44' which pass slidably through the flanges of the roller in a location adjoining the hooked ends of the fingers. The catches are carried by bell cranks 43 and 44 pivotally mounted on the sides of the roller. The bell cranks are connected by coiled springs 45 to spools 46 secured to the shaft 23', and the springs are of such a nature that they normally hold the catches in. Accordingly as the roller 23 rotates, the slugs will be first 90 caught between the fingers and then subsequently engaged by the catches, the catches operating to withdraw the lowermost slug from its position on the foot piece and the fingers acting thereafter to hold the slug in 95 place in the channel of the roller.

After the lowermost slug has been rotated to cause the addressing plate to make contact with the face of the roller 6, it is necessary to remove the slug and this is done by providing the trip bars 47 and 47' underlying the 100

spools 46, and adapted in the rotation of the bell cranks with the roller 23, to actuate the bell cranks in a manner such that the catches thereof will be withdrawn. The withdrawal 105 of the catches takes place before the advancing side of the moving slug is brought into contact with a vertically disposed stop plate 48, the upper end of which is entered between the channels. Obviously the stop plate in 110 engaging with the slug, will hold the slug and the fingers will then slide past the ends of the slugs after which time the slug is free to drop.

Opposing, spaced guide rods 49, suspended 115 in a similar manner to those 28 and 29, are provided underneath the roller 23 to catch each slug as it is released from the roller. The released slugs will accordingly slide down the rods 49.

In the present instance I show these slugs 120 escaping from the lower ends of the rods, but they could be readily retained in stack form so that when the run has to be repeated, they would be all lined up for replacement on the 125

upper rods 28 and 29. I have shown a limited number of slugs in the stack, but it will be understood where a lot of periodicals are to be addressed, new stacks of slugs 5 would be required to be fed to the rods.

Adjoining the roller 23 and driven thereby, I locate an inking roller 50 which rides the flanges 24' and is adapted, in the rotation of the roller 23, to ink the type of the addressing 10 plate 39. The inking roller contacts with a feed roller 51 operating in an ink well 51'. These latter rollers are carried by suitably supported cross shafts 52 and 52'.

The roller 13 carries a lengthwise extending cutting blade or knife 53 which, in the present instance, is shown as provided with sharpened teeth. The roller 12 is supplied with a lengthwise extending slot 54 which, in the rotation of the rollers 12 and 13, is 20 adapted to receive the edge of the knife.

Immediately adjoining the slot 54 I locate a gumming pad 55 which is gummed once every revolution of the roller 12 by a gumming roller 56 which is in rolling contact 25 with a feed roller 57 operating in a well 57' for mucilage or such like liquid sticking material.

According to the above arrangement, it will be obvious that each time the rollers 12 30 and 13 rotate a complete revolution, they will cut the paper and apply the mucilage or such like sticking material to the paper, the applying of the mucilage occurring before the paper is cut, with the result that a gummed 35 strip of paper, which I call a wrapper, is expelled from the rollers 12 and 13, the gum being applied at the rear edge of the wrapper. The circumference of the rollers is gauged so that the length of paper cut off each revolution by the knife will be of a pre-determined 40 proper length to subsequently wrap the periodical introduced into the machine. The wrappers gummed and cut to the proper length and also addressed, are delivered by 45 the rollers 12 and 13 on to horizontally disposed receiving fingers 58 and 58' carried by the rear end of the machine and these receiving fingers direct the wrapper to the periodical wrapping apparatus, now described in detail.

Rearwardly of the machine I locate a pair of vertically positioned, spaced, opposing, substantially U-shaped, end brackets 59 and 60 which are suitably supported from the 55 base of the machine, each bracket being formed with a forwardly positioned, horizontally disposed entry pocket 61 which is adapted to receive the forward edge of the periodical entered in a horizontal lying position within the brackets, the periodical being passed into place from the rear and end of the machine between the open ends of the brackets. The fingers 58 and 58' are supported by braces 62 secured to a cross 60 bar 63 carried by the brackets 59 and 60, and

here it will be observed that the rear ends of the fingers are disposed approximately mid-way of the height of the pocket 61 so that the advancing edge of the periodical can pass into the pockets immediately under the 70 rear ends of the fingers and be stopped by the braces 62, whilst the wrapper previously gummed and addressed has the rear edge thereof resting on the rear ends of the fingers and overlying the advanced edge of the inserted periodical.

The rear end of the machine carries at the front side, a pair of elevated bearings 64 and 64' and these receive rotatably, a comparatively short shaft 65, the forward end of 80 which is fitted with a pinion 66 and the inner end of which carries a T-head 67. The head supports two parallel, suitably spaced, folding rods 68 and 69, which when the periodical is entered, are located one above and 85 one below the same. These rods are adapted to rotate with the head within the open centres of the brackets 59 and 60, and the said brackets are more or less concentric to the shaft 65.

The brackets 59 and 60 carry a plurality of equi-spaced cross rods 70 grouped concentric to the shaft 65. The cross rods carry similar U-shaped pressure plates 71 and are also provided with short outstanding posts 72 connected by coiled springs 73 to the U-shaped brackets 59 and 60. Stop pins 74 are carried by the brackets and engage the posts, these pins limiting the swinging in one direction of the pressure plates under the influence of 100 the springs 73.

When the periodical is entered in the machine as previously described, it passes also between the rods 68 and 69 and between the lower pairs of pressure plates, and when the shaft 65 is rotated in a counter clockwise direction, the upper wrapping rod strikes the periodical and the overlying edge of the wrapper and carries them down, and in the continued rotation of the shaft 65, the paper 105 is rolled around the rods and is held in by the pressure plates which in the initial rolling of the periodical, swing out to accommodate the periodical, but are restrained by the springs 73.

The shaft 65 is rotated several times by the pinion 66 which meshes with a fixed number of teeth 75 carried by a gear wheel 76, this gear wheel being mounted and driven by a power shaft 77. The teeth 75 are designed 120 to rotate the shaft 65 a fixed number of revolutions so that it starts and stops with the folding fingers in the vertical position as shown best in Figure 5. Suitable means is provided to lock the pinion 66 so that it will 125 always mesh in with the teeth 75. Such means, in the present instance, is in the form of a shoe 79 attached to the shaft 65, the shoe being adapted to pass onto and ride a flange 79' carried by the gear wheel 76 just as the 130

teeth of the pinion and those of the gear wheel 76 are going out of mesh. The flange continues to hold the shoe in a fixed position until the pinion is again brought into mesh with the teeth 75 at which time the shoe rolls off the end of the flange and rotates with the pinion.

The inner end of the power shaft, which can be belt or otherwise driven, is provided with a gear wheel 80 and between the gear wheel 80 and that 19' I locate a train of intermeshed gears 81 which cause the gear wheel 80 to drive that 19' in a proper direction.

After the periodical has been wrapped, it is removed from the machine by a grabbing device shortly described which is timed to grab the end of the periodical immediately following the wrapping operation, and after having grabbed the periodical is moved out to withdraw the same endwise from the wrapping rods and then after having released the wrapped periodical, remains out until the following periodical has been wrapped when it again moves in and duplicates its action.

At the rear side of the machine I locate a vertically disposed, rotatably mounted shaft 82 which has the upper and lower ends thereof provided with bevel pinions 83 and 83' the pinion 83 meshing with a pinion 84' located on the rear end of the shaft 8. An arm 84 is pivotally swung from the shaft 82 and carries on the under side a pair of bearings 84' and 84'' which support rotatably a counter shaft 85 fitted with pinions 85' and 85'', the pinion 85' meshing with that 83'.

According to the arrangement shown, it will be apparent that the shaft 85 will be driven at all times by the shaft 82 irrespective to the position of the arm 84.

The bevel pinion 85'' meshes with the bevel pinion 86' located at the lower end of a vertically disposed shaft 86 carried by the arm 84 and to the other end of the shaft 86 I secure a gear wheel 86''. The arm 84 also carries a second short shaft 87 on which a gear wheel 87' rotates, this gear wheel being in continuous mesh with the gear wheel 86''.

A pair of L-shaped cranks 88 and 89 are rotatably mounted on the shafts 86 and 87 beneath the gear wheels thereon, and the cranks are provided with intermeshed teeth 88' and 89' and also with a pair of upstanding shafts 88'' and 89''. A coiled spring 90 connects the cranks and normally draws the shafts together.

On the shafts I mount a pair of similar rollers 91 and 91' and to the lower ends of the rollers I secure pinions 91'' which mesh with the gear wheels 86'' and 87'. An upper coiled spring 90' connects the upper ends of the shafts 88'' and 89'', this spring co-operating with the spring 90 to draw the rollers together.

From the above arrangement it will be ap-

parent that the shaft 85 will drive the gear wheel 86'' and this gear wheel operates to rotate through the gear wheel 87' and pinions provided to continuously rotate the rollers 91 and 91' in the direction of the applied arrows, Figure 2. The rollers while being driven are free to swing apart, this being provided for in the cranks 88 and 89, and the rollers will swing equally on account of the intermeshed teeth 88' and 89'.

A coiled spring 92 connects the arm 84 with the base 1 of the machine and normally holds the arm in. Means is provided for moving the arm outwardly at the proper time, such embodying a cam 93 formed on one end of the roller 13 and a push rod 94 is slidably carried by the base 1 and having the inner end thereof riding the cam and the end of the roller, and the outer end thereof connected pivotally by a link 95 to the arm 84. The arrangement of the cam is such that immediately following the winding and wrapping of the periodical, the rollers 91 and 91' will move in and grab the exposed end of the wrapped periodical, it being noticed that the direction and rotation of the rollers is such that they will draw the end of the periodical between them and also that the mounting of the rollers is such that they can spread apart whilst being driven to accommodate the varying thicknesses of the periodicals grabbed.

The cam control is also designed so that the rollers, after gripping the periodical, will move out so that the wrapped periodical will be entirely clear of the machine so as not to interfere with the placing in the machine of another periodical to be wrapped. After having moved out, the rollers stay out until the next periodical is wrapped.

From the above it will be obvious that this machine is entirely automatic in the work of addressing, wrapping and expelling the periodicals fed into the same.

What I claim as my invention is:—

1. In combination, a driven roller having a peripheral channel therearound, a stack of address bearing slugs having the lowermost slug of the stack entered within the channel, a foot piece supporting the lowermost slug, catches carried by the roller and operating through the sides of the channel and adapted to cause the lowermost slug to turn with the roller when the catches engage the slug, means for frictionally holding the caught slug within the channel for a portion of a revolution of the roller and means for subsequently withdrawing the slug from the channel.

2. In combination, a rotatably mounted and driven roller provided with a continuous peripheral channel, a plurality of address bearing slugs arranged in the form of a stack above the roller and with the lowermost of the stack in the channel, a foot piece supporting the lowermost slug in the latter position, a pair of spring pressed fingers carried by

the roller and adapted to catch the ends of the lowermost slug of the stack once each revolution of the roller, a pair of opposing catches carried by the roller and operating through the sides of the channel and adapted to engage the lowermost slug of the stack subsequent to the same being caught by the catches and to withdraw said slug from the

foot piece, means for subsequently releasing the catches, and a stop plate engageable with the slug subsequent to the release of the catches.

Signed at Winnipeg this 26th day of November, 1924.

THOMAS MENZIES.
